UNITED STATES PATENT OFFICE.

CHARLES WILLIAM COUCHE, OF LIVERPOOL, AND JAMES KENYON, OF FLIXTON, NEAR MANCHESTER, ENGLAND.

COOLING APPARATUS FOR USE IN SOAP MANUFACTURE.

Application filed June 14, 1921. Serial No. 477,540.

To all whom it may concern:

Be it known that we, CHARLES WILLIAM COUCHE, of 22 Blantyre Road, Smithdown Road, Liverpool, in the county of Lancaster, 5 England, and JAMES KENYON, of Woodville, Moorside Road, Flixton, near Manchester, England, subjects of the King of Great Britain and Ireland, have invented certain new and useful Improvements in Cooling 10 Apparatus for Use in Soap Manufacture, of which the following is a specification.

This invention relates to apparatus for use in the cooling of soap during its manufacture and has for its object to provide a reliable and efficient cooling apparatus which shall not be subject to the disadvantages of coolers such as at present in use in which the cooling water channels are formed in cast metal frames having polished or non-rusting cover plates attached thereto with which the soap being cooled contacts.

Referring to the accompanying sheet of explanatory drawings:—

25 Figure 1 is an elevation of the cooler frame with part of the cover plate removed.

Figure 2 is a plan view of the frame with the top cover plate removed.

Figure 3 is a sectional plan view on the 30 line A B of Figure 1.

The same reference letters in the different views indicate the same parts.

In accordance with our invention, we form the cooling frames *a* of suitable wood, 35 such as teak, the said frames being of grid-like form, open at the opposite sides and having the necessary vertical division pieces *b* to divide the water space into a number of parallel passages *c*, each having a separate supply and outlet connection *d* and *e* at its lower and upper ends respectively. Each frame is also provided with a passage *f* for the inflow of the liquid soap to the cooling space which is disposed in the 40 known manner between two cooling frames. The passage is fitted with a metal sleeve *g* which is riveted or headed over at its ends upon the cover plates (see Figure 3).

The opposite sides of each cooling frame 45 are provided with cover plates *h* made preferably of a non-rusting metal, the plates being secured in place by screws which may be of the same metal as the plates to prevent electrolytic action.

The vertical divisions in the cooling 55 frame may be tapered or chamfered off at their opposite sides as shown in Figure 3 to reduce their area of contact with the cover plates and so provide a maximum area of cover plate exposed to the cooling water. 60

When the cooling frame has been assembled with its cover plates in position, the same may be filled with hot bitumastic paint which is allowed to stand for a short period to ensure that the whole of the wood 65 surface and also the inside faces of the cover plates receive a protective covering. The excess of paint is then drained off. The screw holes in the cover plates may be 70 likewise painted with bitumastic paint before the screws are placed in position to prevent metallic contact between the screws and the plates.

Water troughs *i*, *j* are provided in the bottom and top of the frame, each trough 75 being closed by a cover plate.

It will be seen that with our improved construction of cooling frame, there is only the thickness of the metallic cover plates between the cooling water and the soap being cooled, which ensures high efficiency. Further, the weight of the coolers is very considerably reduced and owing to the 80 treatment with bitumastic paint the growth of fungus in the cooler is minimized. 85

We do not limit ourselves to any particular shape of the water channels in the cooling frames nor to any particular material for the cover plates. The latter in our improved construction do not bulge and diminish the space occupied by the soap as do the cover plates of present constructions of coolers for soap. The cover plates are preferably of the same overall dimensions as the sides of the wooden grid or frame to which 90 they are attached so as to protect the wood 95 against damage.

We claim:—

1. Wooden frames for cooling apparatus for soap of grid-like open form at the opposite sides and having vertical division pieces arranged to divide the enclosed space into a number of parallel passages, each having a separate water supply and outlet connection; a passage for the flow of the 100 liquid soap to the cooling space between adjacent frames and cover plates attached to the opposite sides of the frames, as set forth. 105

2. In cooling frames as claimed in claim 1, the provision of water troughs in the top and bottom of the frames, as set forth.

3. In cooling frames as claimed in claim 5 1, the vertical division pieces being formed in cross section so that they taper towards the opposite sides of the frames to reduce

their area of contact with the cover plates as set forth.

In testimony whereof we have signed our 10 names to this specification.

CHARLES WILLIAM COUCHE.
JAMES KENYON.
